UNITED STATES PATENT OFFICE.

HENRY C. STOLL, OF NEW YORK, AND GEORGE W. GAY, OF ELMHURST, NEW YORK.

INTERNAL-COMBUSTION ENGINE.

1,193,629.

Specification of Letters Patent.

Patented Aug. 8, 1916.

Application filed August 17, 1915. Serial No. 45,856.

To all whom it may concern:

Be it known that we, HENRY C. STOLL and GEORGE W. GAY, citizens of the United States of America, residing, respectively, at 5 New York and Elmhurst, New York, have invented a new and useful Internal-Combustion Engine, of which the following is a specification.

This invention relates particularly to engines of the sliding valve type, and the objects of the invention are to improve, simplify and increase the efficiency of engines of this character.

Further and special objects of the invention are to reduce the wear and friction of the valve gear, to provide adequate lubrication for the valves, and to reduce the speed of valve movement.

These objects we have accomplished by 20 the employment of slide valves having ports to register with intake and exhaust ports in the cylinder of the engine and by operating these valves from the crank shaft at a speed ratio corresponding to one to four. This 25 valve action causes the valves to travel from a point where the ports therein are disposed at one side of the ports in the cylinder to a point where said ports are disposed at the opposite side of the ports in the cylinder 30 during one cycle of operation, and from a point at said last mentioned side of the cylinder ports on past said cylinder ports to the further side thereof during the next cycle of operation. This gives an easy relatively slow valve movement with ample 35 clearance, and permits of the attainment of much higher engine speeds than have heretofore been possible in engines of this general type.

40 The valves preferably work in direct engagement with the wall of the cylinder, and are preferably of sleeve construction. A special feature consists in making the valves in the form of interfitting sliding sleeve segments, oppositely disposed segments being connected at top and bottom so as to move as a unit, and the opposite segments both being ported so as to relieve the valves of unequal pressure.

45 Other features of the invention reside in the novel form of valve actuating mechanism employed, which feature, and other features as well, will appear as the specification proceeds.

In the accompanying drawings we have 55 illustrated different forms the invention may take, but we would have it understood that changes and modifications may be made without departing from the true spirit and scope of the invention.

60 In the drawings: Figure 1 is a vertical section view of an engine constructed in accordance with and embodying the invention, certain parts being shown in elevation and broken away. Fig. 2 is a sectional view 65 taken substantially at a right angle to the plane of Fig. 1 approximately on the line 2-2 of Fig. 1. Fig. 3 is a horizontal section view of the cylinder and valves taken substantially on the plane of the line 3-3 70 of Fig. 1. Fig. 4 is a sectional view of the same, taken substantially on the plane of the line 4-4, Fig. 1. Fig. 5 is a vertical section view of the valve and valve housing taken substantially on the plane of the line 75 5-5, Fig. 1. Fig. 6 is a detached perspective view on a smaller scale of the segmental exhaust valve. Fig. 7 is a similar view of the segmental intake valve. Figs. 8, 9 and 10 are diagrammatic views of different 80 forms of valve gearing. Figs. 11 to 18 are diagrammatical representations showing the parts in successive positions.

85 In the illustrations, referring particularly to Fig. 1, 20 designates an engine cylinder, and 21 a piston working therein and connected by a connecting rod 22 with the crank shaft 23. The cylinder is provided with intake and exhaust ports 25 and 26 in the walls thereof opening into the compression space 90 at the head end of the cylinder. In order to equalize the pressure, the said ports would preferably be arranged in pairs, one diametrically opposite the other. Thus in Fig. 1, two diametrically opposite inlet ports are 95 shown, and it will be understood that another exhaust port will be provided in the cylinder wall opposite the one shown in that figure.

100 28 designates the intake valve and 29 the exhaust valve. These valves, as more fully appears in Figs. 6 and 7, are, in the embodiment illustrated, in the form of oppositely disposed sleeve segments 28^a and 29^a united at their ends by rings or collars 28^b and 29^b, 105 constructed and arranged to slide directly over the outside surface of the cylinder. In the particular construction illustrated, the

four valve segments constitute, when assembled, a complete cylinder and the meeting edges of the segments are interfitted by zig-zag or Z-shaped joints 30 which brace the segments and prevent leakage. The assemblage of these valves is accomplished by sliding the one valve endwise into engagement with the other valve. Thus, in the illustration, the exhaust valve (Fig. 6) would be slid down over the head of the intake valve shown in Fig. 7, the valve segments 29^a of the exhaust valve being received in between the valve segments 28^a of the intake valve, the connecting ring 29^b on the lower end of the exhaust valve being reduced in between the segments 29^a substantially as indicated, so as to slide over the segments 28^a of the intake valve.

The intake valve is provided in the opposite segments thereof with intake ports 31 and similarly the exhaust valve is provided with exhaust ports 32. These ports in the valves are of a size and shape and are so positioned as to register with the corresponding ports in the cylinder wall.

The gearing for operating the two valves, in the first form of the invention illustrated, comprises in each instance a valve crank shaft 35 journaled in the crank case 36, connected by a rod 37 with a rod 38 secured to the valve and operated from the engine crank shaft by four to one gearing in the form of a pinion 39 on the engine crank shaft, and a gear 40 of four times the number of teeth on the valve crank shaft 35. One set of such valve gearing is shown in Fig. 2, and it will be understood that a duplicate set of gearing for the other valve will be provided at the opposite end of the crank case. The connecting rods and cranks for both the valves are shown in Fig. 1, and both the connecting rods are shown in Fig. 5. In these views the valve rod 38 is engaged with the lug 41 on the bottom ring of the exhaust valve 39, and the valve rod 38^a for the intake valve engages with a similar lug 41^a on the bottom ring of the intake valve. The connecting rod for the intake valve is designated 37^a and the crank for this valve is designated 35^a. These connecting rods are looped or otherwise constructed, so as to work past the engine crank shaft and the intake valve crank, as most clearly shown in Fig. 1, set at an angle of approximately 45° behind the exhaust valve crank.

From the foregoing description it follows that the valve cranks will be rotated once to each four revolutions of the engine crank shaft. In Fig. 1, the piston is in the intermediate position of its compression stroke and both valves are closed. In Fig. 11 the piston is shown at the upward limit of its stroke in the firing position. In the interim of time between these two positions of the

parts, the exhaust valve has started on its downward stroke, and the intake valve has almost reached the upward limit of its stroke. In Fig. 12 the piston is half-way down on its power stroke, the exhaust valve 70 is being moved toward open position and the intake valve has reached the upward limit of its stroke. In Fig. 13 the piston is at the end of its power stroke, the exhaust valve is about to open, and the intake valve has 75 just started to move toward open position. In Fig. 14 the piston is traversing the intermediate portion of its exhaust stroke, the exhaust valve is open, and the intake valve is almost ready to open. In Fig. 15 the 80 piston is in the head of the cylinder and the exhaust ports are closed and the intake valve is just commencing to open. In Fig. 16 the piston is part-way down on its suction stroke, the ports in the exhaust valve have 85 been carried down past the cylinder exhaust ports and the intake ports in the intake valve have been carried down into register with the cylinder intake ports. In Fig. 17 the piston has reached the end of its suction 90 stroke, the exhaust valve is still moving downward and the intake ports are closed. In Fig. 18 the piston has again started upward on its compression stroke, the exhaust valve has moved downward to its extreme 95 lower position, and the intake valve is still moving downward, both exhaust and intake ports being closed. The engine has in these views thus completed one entire cycle of operations, and the only valve movement 100 necessary has been that to carry the valve ports from a position above the cylinder ports down past said cylinder ports to a position below the same. In the completion of the next cycle, it will be apparent that 105 the valve will simply move to carry the ports therein from this position below the cylinder ports up past and beyond the cylinder ports. The valve motion will thus be seen to be relatively slow and steady, 110 reducing friction and vibration to a minimum and permitting of the attainment of very high engine speeds.

The valve rods have, as indicated at 45 in Fig. 1, a very substantial bearing and 115 work straight up and down so that side thrust is reduced to a minimum. The oppositely disposed ports in the valves balance the pressure on the valve, and serve to further reduce friction and wearing of the 120 parts.

Packing rings 46 and 47 are preferably provided on the cylinder at points above and below the ports therein to prevent leakage of gas.

The valves are preferably inclosed within a housing 50 which may be secured in place by bolting it to the crank case, as indicated at 51. This housing is shown provided at the top with a downward annular extension

- 52 engaging the head of the cylinder to thereby serve to secure the cylinder to the crank case. An oil reservoir 53 may be provided in the bottom portion of the valve housing for lubricating the valves and valve operating mechanisms. The valve housing is provided with openings, as indicated at 25° in Fig. 1, registering with the intake and exhaust ports in the cylinder.
- 10 Different methods may be employed for cooling the engine. For instance, air cooling fins could be provided on the outside of the valve housing. The several intake or exhaust ports in the cylinder may be connected by means of outside piping or by coring suitable interconnecting passageways in the wall of the cylinder.
- 15 It will be understood that various other forms of gearing for operating the valves may be employed, such for instance as indicated in Figs. 8, 9 and 10.
- 20 In Figs. 8 and 9 a twin cylinder engine is illustrated diagrammatically, having a pinion 60 on the crank shaft thereof meshing with the gear 61 of four times the size which carries two crank pins 62 and 63 connected by links 64, 65 and rods 66, 67 with the valves of the respective cylinders. To prevent interference between the two 25 crank pins and the parts operated thereby, the outer crank pin 63 may be mounted on an off-set carried by the inner crank pin 62 as will be readily understood. This mechanism as in the first case illustrated 30 would be duplicated at the opposite end of the crank shaft for operating the other valves of the two cylinders.
- 25 In Fig. 10 a convenient method of operating the valves of a multi-cylinder engine is illustrated. Here there is provided a valve crank shaft 70 connected by reduction gearing, such as the silent chain and sprocket connection 71 illustrated, with the crank shaft 72, the connecting rods 73 and valve rods 74 serving to transmit the motion of the valve cranks to the respective valves.
- 30 From the foregoing it will be seen that the engine of our invention is extremely simple and practical and that the valving mechanism gives great efficiency.
- 35 What we claim is:
1. In an internal combustion engine, a cylinder having diametrically opposite intake ports and diametrically opposite exhaust ports in the side wall thereof, diametrically opposite intake valve segments engaging the diametrically opposite portions of the cylinder wall in which the intake ports are formed, said intake valve segments having ports therein to register with the intake ports and connected together so as to move in unison, diametrically opposite exhaust valve segments engaging the diametrically opposite portions 40 of the cylinder wall in which the exhaust ports are located, said exhaust valve segments being connected to move in unison and provided with ports to register with the cylinder exhaust ports, a crank shaft, a piston in the cylinder connected with said crank shaft and valve operating gearing between the crank shaft and the connected valve segments.
  2. In an internal combustion engine, the combination of a cylinder having ports in the cylindrical side wall thereof, a segmental valve construction comprising four valve segments in sliding engagement with the cylindrical side wall of the cylinder and in sliding edge to edge engagement with each other, opposite valve segments being connected together to move in unison, a crank shaft, a piston in the cylinder connected with said crank shaft and valve operating gearing between the crank shaft and the connected valve segments.
  3. In an internal combustion engine, a cylinder having ports in the cylindrical side wall thereof, valve segments arranged in oppositely disposed pairs in sliding edge to edge engagement with each other and having a sliding engagement with the cylindrical side wall of the cylinder, opposite valve segments being connected together to move in unison, a crank shaft, a piston in the cylinder connected with the crank shaft and valve operating gearing between the crank shaft and the respective pairs of valve segments.
  4. In an internal combustion engine, a cylinder provided with intake and exhaust ports in the side wall thereof, diametrically opposite intake valve segments sliding over the cylinder, and provided with ports to register with the intake ports, rings connecting the upper and lower ends of said valve segments, diametrically opposite exhaust valve segments slidingly mounted on the cylinder between the intake valve segments and provided with ports to register with the exhaust ports, rings connecting the upper and lower ends of said exhaust valve segments, a crank shaft, a piston in the cylinder connected with said crank shaft, and valve operating means operated by the crank shaft and connected with the lower rings of the valve segments.
  5. In an internal combustion engine, a cylinder provided with intake and exhaust ports in the side wall thereof, diametrically opposite intake valve segments in sliding engagement with the cylinder wall and provided with ports to register with the intake ports in said wall, means connecting said valve segments to cause them to move as a unit, diametrically opposite exhaust valve segments between the intake valve segments and provided with ports to register with the exhaust ports, means connecting said exhaust valve segments to cause them to move as a unit.

- as a unit, a crank shaft, a piston in the cylinder connected with said crank shaft, and valve operating means operated by the crank shaft and connected with the respective sets 5 of connected valve segments.
6. In an internal combustion engine, a cylinder provided with intake and exhaust ports in the side wall thereof, an intake valve comprising diametrically opposite 10 valve segments sliding over the cylinder and provided with ports to register with the intake ports, said segments being connected at the top and bottom by annular connecting means, an exhaust valve comprising oppositely disposed valve segments fitting both 15 the intake valve segments and connected at their lower ends by a ring sliding over the intake valve segments, said exhaust valve segments having ports therein to register 20 with the exhaust ports, a crank shaft, a piston in the cylinder connected with said crank shaft and valve operating gear between said piston and the respective valves.
7. In an internal combustion engine, a cylinder having diametrically opposite intake 25 ports and diametrically opposite exhaust ports in the side wall thereof, an intake valve sliding over said cylinder and having diametrically opposite connected valve segments engaging over the diametrically opposite 30 portions of the cylinder in which the inlet ports are located and provided with ports coöperating with said inlet ports, an exhaust valve slidingly engaged over the 35 cylinder and having diametrically opposite connected valve segments engaging over the diametrically opposite portions of the cylinder wall in which the exhaust ports are located and having exhaust ports therein co- 40 operating with said cylinder exhaust ports, a crank shaft, a piston in the cylinder operatively connected with said crank shaft

and valve operating gearing between the crank shaft and the respective valves.

8. In an internal combustion engine, a cylinder having diametrically opposite intake ports and diametrically opposite exhaust ports in the side wall thereof, an intake valve having diametrically opposite portions in sliding engagement with the diametrically opposite portions of the cylinder wall in which the intake ports are located and provided with ports to register with said cylinder intake ports, an exhaust valve having diametrically opposite portions in sliding engagement with the diametrically opposite portions of the cylinder wall in which the exhaust ports are located and provided with ports to register with said cylinder exhaust ports, a crank shaft, a piston in the cylinder 60 operatively connected with said crank shaft and valve operating gearing between the crank and the respective valves.

9. In an internal combustion engine, a cylinder having diametrically opposite intake 65 ports and diametrically opposite exhaust ports in the side wall thereof, an intake valve having diametrically opposite portions in sliding engagement with the diametrically opposite portions of the cylinder wall in 70 which the intake ports are located and controlling said cylinder intake ports, an exhaust valve having diametrically opposite portions in sliding engagement with the diametrically opposite portions of the cylinder 75 wall in which the exhaust ports are located and controlling said cylinder exhaust ports, a crank shaft, a piston in the cylinder operatively connected with said crank shaft and valve operating gearing between the 80 crank and the respective valves.

HENRY C. STOLL.
GEORGE W. GAY.
